UNITED STATES PATENT OFFICE.

ANITA G. LITTLE, OF GORHAM, MAINE.

DESIGN FOR A COMBINED SEWING OUTFIT AND MATERIAL HOLDER.

Application filed December 31, 1928. Serial No. 29,461. Term of patent 7 years.

To all whom it may concern:

Be it known that I, ANITA G. LITTLE, a citizen of the United States, residing at Gorham, in the county of Cumberland and State of Maine, have invented a new, original, and ornamental Design for Combined Sewing Outfit and Material Holder, of which the following is a specification, reference being had to the accompanying drawing, forming part thereof.

The figure is a perspective view of a combined sewing outfit and material holder showing my new design.

I claim:

The ornamental design for a combined sewing outfit and material holder, as shown.

ANITA G. LITTLE.
